TELEVISION APPARATUS

Hans Knudsen, Streatham, London, England

Application February 25, 1935, Serial No. 8,147
In Great Britain May 31, 1933

6 Claims. (Cl. 178—6)

In existing systems of analyzing and reproducing, in television, images of objects whether moving or stationary, satisfactory results have hitherto been greatly obviated and impeded by the 5 limitations of the apparatus available for use; for example, to obtain a sufficiently large number of light beams and the requisite speed of succession to produce a perfect image a circular scanning disc as now in use has to be of such 10 large diameter that in revolving it becomes unwieldy and the uniformity of its motion is distorted thereby creating irregularly moving light beams and setting up correspondingly irregular electrical oscillations.

15 It is well known that there may be employed as a scanning device an endless band with laterally and longitudinally spaced apertures, so that the longitudinal movement of the band causes the apertures to traverse the area to be scanned. It has been proposed to employ such 20 a scanning device in conjunction with one or more cells or light sources situated behind the band and extending across the longitudinal dimension of the scanned area, the cells or light 25 sources being moved in step by step fashion laterally across the scanning band while the band moves longitudinally. By such an arrangement, when the picture is analyzed into thirty lines, each complete scanning occupying one-six- 30 teenth of a second, it will be seen that a single lamp will be required to move forward at the rate of 480 steps per second, which rate of motion is in practice difficult to attain, while such a movement is detrimental to the structure of the 35 cells or light sources.

The object of my invention is to overcome these difficulties principally by providing that the cells or light sources shall be moved laterally across the scanning band in a continuous instead of in a step-by-step fashion. Other 40 advantages will be disclosed in the following description of my invention.

According to this invention I provide an improved method of and means for analyzing and/or 45 reproducing images of objects by television consisting of the combination in television apparatus of two synchronously and transversely moving members, the one comprising an endless metallic band provided with laterally and longitudinally 50 spaced apertures extending obliquely across the inner portion of the surface of the said band, the other comprising a carrier band for automatically operated light-sensitive and light-projection units for receiving and projecting light rays from 55 or upon every successive aperture in the first

member, each of the said units being moved upon the carrier band so as to traverse continuously the path of the scanning band and to receive or to project the said light rays in a continuous and concentrated beam converging at a specific point. 5

The invention is illustrated in and by the accompanying drawings, reference to which will be made in the following description under the respective figures in all of which like numerals and letters refer to like parts of the apparatus. 10

Figure 1 is a side sectional view of the invention as arranged for transmitting and analyzing;

Figure 2 is a front view of the scanning band;

Figure 3 is a plan view of the photo-electric unit as it moves across the surface of the scanning 15 band;

Figures 4, 5, and 6 are side sectional views of one of the photo-electric cells shown in Figure 3.

Figure 6a is a plan view of Figure 4;

Figure 7 is a sectional view of the frame and 20 rollers bearing the carrier band;

Figure 8 is a side view of the above frame;

Figure 9 is a side sectional view of the invention as arranged for receiving and reproducing;

Fig. 10 is a plan view of a reproducing unit comprising a neon-argon tube and its holder, the 25 parts being shown unassembled.

Fig. 10a is a side elevation of the tube and holder shown in Fig. 10.

Fig. 11 is a plan view of another form of re- 30 producing unit comprising a neon-argon tube and a double convex lens.

Fig. 11a is a side elevation of the arrangement shown in Fig. 11.

Fig. 12 is a plan view of a holder for the ar- 35 rangeement shown in Figs. 11 and 11a.

Fig. 12a is a side elevation of the holder shown in Fig. 12.

In Figure 1 A is a screen or stage on which a display of performance is made, B, B, are arc 40 lights directed upon the objects to be recorded. C is an upright casing or chamber in the top and bottom of which are located in reversed position the metal frames 2, 3, upon which are mounted the pulley wheels 5, 6. The shaft 4 of the pulley 45 wheel 5 is connected to the main drive motor 7 so as to be driven thereby while the other pulley wheel 6 is adapted to turn freely upon the shaft 8. Upon the shaft 4 is also arranged a suitable gearing unit g and band h adapted to regulate 50 rotation of the sprockets 30, 31 (Figure 3) with regard to the rotation of the pulley wheels 5 and 6. These pulleys are provided with sprocket teeth 9, 10 over which passes, in close proximity to the front and rear walls of the case or chamber, the 55

metal band 11. At a suitable distance between the pulley wheels and fixed to the side walls of the case is arranged a shelf 12 carrying the electrically energized unit 13 provided with suitable connections 14 to the amplifier 15 which rests upon another shelf 16 mounted upon brackets 17 in the side walls of the casing but at a suitable distance from the front and rear walls thereof. The amplifier 15 is provided in the customary manner with terminals 20, 21 for external connection to the transmitters or aerials. 18 is a telescopically adjustable lens which is firmly clamped at 19 within the exterior of the casing.

Figure 2 shows a frontal view of the scanning band 11 which is recessed at its inner portion 22 while the lateral extremities 23 are provided with perforations 24, 25 which fit upon the teeth 9, 10 of the pulley wheels. The inner portion 22 is provided with the apertures 28 which proceed in oblique ascendancy in series 26a—b, c—d . . . to x across the face of the band 11. These apertures are preferably arranged in square formation so that the outer side of p of a succeeding aperture is in line with the inner side q of the preceding aperture, while the distance between the top of one aperture and the base of its successor may be of any suitable proportion for the required purpose. In practice it has been found that this distance approximates one and a half inches, while the size of the aperture should not exceed the thickness of the band; thus, given a band of which the inner portion has been recessed to a thickness of 0.004 of an inch, the number of apertures which made in such a band 35 should not exceed 250 to the inch. To provide a similar number of apertures in the standard type of scanning disc the diameter of the said disc would have to exceed 8 feet and an appropriate thickness, thereby rendering the apparatus unwieldy and irregular. The band 11 travels downward in the course of the arrow and successive portions as between the lines k k pass before the lens 18 the light from which penetrates each successive aperture in the band during the 45 whole period of the movement of the said aperture from the top to the bottom of the space k, k. Thus a series of perpendicular lines of light in plane with each other is built up.

Figure 3 shows a plan view of the automatically operated carrier system for the electrically energized units 13 with a section of the casing wall 27 in which is mounted the telescopic lens 18. Facing the lens is a line of the scanning band 11 showing the lateral extremities 23 with the perforations 24, 25 and the recessed inner portion 22. In this case the electrically energized unit is a photo-electric cell 28 mounted upon the carrier member 29 which is adapted to travel over the sprocket wheels 30, 31. 32 is a plan view of the carrier frame which is mounted upon the shelf 12 in the casing. 33 is a double convex lens sealed in the tubular wall 34 of the cell 28 through which lens 33 pass rays from each successive aperture in the band 11. These rays pass from the telescopic lens 18, are enlarged as at 1, condensed and made to converge in strengthened ray form as indicated in the drawings at the anode 35 and are transformed into electrical energy by the action of the cathode of variable power corresponding to the variations of the reflected light rays. The cell 28 is mounted at a distance from the surface of the band 11 equivalent to the focal length of the double convex lens 33 so that the full power of the strengthened light beam is 70 concentrated upon the cathode in serial form.

The cell 28 is carried along the path of the carrier band 29 by the revolution of the sprocket wheels 30, 31 at a uniform rate, and is synchronized with the movement of the band 11 by means of the gearing g (Figure 1) so that the lens 33 picks up and absorbs a perpendicular series of light rays from each successive aperture in the scanning band 11 as the cell moves transversely across the path of the said band. When one cell has completed the full passage across the surface of the scanning band (as shown at 28a) the following cell will have reached the starting point of the band (as at 28b) and this operation will be repeated by each cell in turn. In this way it is provided that an image or images of any object or objects may be divided into a large number of light rays forming perpendicular beams of light of variable intensity which may be separately and uniformly received, condensed, amplified and converted into electrical energy, which in turn may be transformed and emitted as electrical power or hertzian waves for reception and reproduction as light rays reproducing a like image at any desired distance. 25

Figures 4, 5, and 6 are upright sectional views of the cell 28 in which 37 is the argon gas chamber in the wall of which is the double convex lens 33; 38 are recesses for the glass plugs 39, 40 is a support member for the anode 35, 41 is the positive contact, 42 the negative contact, 36 the cathode formed by a semicircular plate; 39 are glass plugs forming insulators for the contact members 41 and 42 adapted to fit into the recesses 38. Figure 6a shows a plan view of Figure 4 with the members 33, 35, 36, and 42 in respective position to the scanning band 11.

Figure 7 is a sectional view of the frame 32 for the carrier member 29 mounted upon the shelf 12. 29 is revolved upon the sprocket members 30, 31, mounted upon the spindles 44, 45, the first of which is connected through its extension 46 to the synchronizing gear g of the main drive motor 7 (Figure 1), 47 are insulating members for the contact holders. Figure 8 is a side view of the frame 32 showing the respective contact strips 48, 49, for the positive and negative terminals 41, 42.

Figure 9 is a side sectional view of the interior of a reproducing set arranged for the reception of waves transmitted from a recording set as shown in Figure 1. In this case all the constituent parts, with the following described exceptions, are similar to those described and shown in Figure 1 and are referred to under like numbers. The receiver 50 is coupled as at 51 to the amplifier 15 which in turn is connected to the electrically energized unit 13.

For the purpose of reception this unit is a series of three or more neon-argon cells 52 and is located in the case or chamber 1 which in this instance is arranged as an enlargement 33 on the front of the case forming a cupboard which may be provided with a door 54 through which the unit 13 may be reached for adjustment from the exterior of the casing. In this case the unit 13 is arranged on the external side of the scanning band 11 while the telescopic lens 8 is mounted within the chamber on the inner side of the said band. Arranged in suitable position within the chamber is a mirror 55 upon which the light rays reproduced in the unit 13 from the received electrical impulses are thrown in their successive order as perpendicular beams of such magnified intensity that there is reproduced an image or 75

images of the objects as originally recorded and transmitted, which image or images may in turn be reflected from the mirror 55 upon a screen in enlarged formation.

- 5 Figs. 10 and 10a show one form of reproducing unit comprising a neon-argon tube 52 mounted within an open frame 56 and enclosed on three sides by a suitable reflecting member such as a mirror 57 and having located in position before 10 it a double convex lens 33; 58 is a platinum filament held between the positive and negative contacts 59, 60. 61, 62 are flexible contact strips for the respective contacts 59, 60, and 63 are rivets for fastening the complete unit in position on 15 the carrier band. In these figures the respective parts are shown in unassembled position. Figs. 11 and 11a show another form of reproducing unit in which the neon-argon tube 52 and the double convex lens 33 are moulded within a glass 20 tube 65 provided with a silvered inner portion of its wall 64 and with glass plugs 66, 67 for retaining the tube 52 in position. The topmost plug 66 is provided with a small arcuate extension on its periphery into which the lens 33 may 25 be moulded. This unit may be encased in a metal holder (Figs. 12 and 12a) of semi-circular form 69 but provided with the circular roof and base, 70, 71 and the rivets 63. 68 is an arcuate extension on the periphery of the roof member 70 30 arranged to accommodate the extension of the plug 66.

From the foregoing description it will be seen that this invention provides a simple and practical means for the transmission and reception of 35 images by television at greatly increased speed together with an effective method of securing the retention of the purity of the light rays emitted as well as the selection of the greatest possible number thereof and their magnified intensity 40 prior to transmission. Since the two motors are running at uniform speed at a distance from each other and the scanning members and electrically energized units are moving at regular speeds synchronously with the motors, the whole motion is 45 uniform and the speed at which these light rays may succeed each other and be selected for recording, transmission and reproduction provide that these reproductions shall retain and display all the refinements of the images of the 50 original objects.

I claim:—

1. Television transmitting apparatus including an optical system for forming an image of the object to be transmitted, an endless band formed 55 with a plurality of scanning apertures arranged in staggered formation, means for continuously moving said band linearly at uniform speed substantially in a plane parallel to the plane of said image so as to scan the image and so that at any given time the portion of the band which is within the image field defines a straight line in said first mentioned plane, an endless belt bearing a plurality of tubular photo-electric cells for receiving light passing through said scanning apertures, said photo-electric cells comprising a single element tube of a length sufficient to extend across the image frame, and means for continuously moving said belt linearly at uniform speed in a direction transverse to that of said band so that 60 said photo-electric cells as they pass the band move in a straight line.

2. Television transmitting apparatus including an optical system for forming an image of the object to be transmitted, an endless metal band formed with a plurality of scanning aper-

tures arranged in staggered formation, means for continuously moving said band linearly at uniform speed substantially in a plane parallel to the plane of said image so as to scan the image and so that at any given time the portion of the band which is within the image field defines a straight line in said first mentioned plane, an endless belt bearing a plurality of tubular photo-electric cells a transparent wall of each of which is formed as a cylindrical lens for focusing light passing through said scanning apertures on to the photo-electric surface of the cell, said surface being comprised of a single element of a length sufficient to extend across the image frame, and means for continuously moving said belt linearly at uniform speed in a direction transverse to that of said band so that said photo-electric cells as they pass the band move in a straight line.

3. Television transmitting apparatus including an optical system for forming an image of the object to be transmitted, an endless metal band the center portion of which is thinner than the edges and is formed with a plurality of square scanning apertures arranged in staggered formation and of diameter not less than the thickness of said band, means for continuously moving said band linearly at uniform speed substantially in a plane parallel to the plane of said image so as to scan the image and so that at any given time the portion of the band which is within the image field defines a straight line in said first mentioned plane, an endless belt bearing three tubular photo-electric cells a transparent wall of each of which is formed as a cylindrical lens for focusing light passing through said scanning apertures on to the photo-electric surface of the cell, said cell being comprised of a single element of a length sufficient to extend across the image frame, and means for continuously moving said belt linearly at uniform speed in a direction transverse to that of said band so that said photo-electric cells as they pass the band move in a straight line.

4. Television transmitting apparatus including an optical system for forming an image of the object to be transmitted, an endless metal band the center portion of which is thinner than the edges and is formed with a plurality of scanning apertures arranged in staggered formation and of diameter not less than the thickness of said band, means for continuously moving said band linearly at uniform speed substantially in a plane parallel to the plane of said image so as to scan the image, and so that at any given time the portion of the band which is within the image field defines a straight line in said first mentioned plane, an endless belt bearing three argon-filled, tubular photo-electric cells each having a semi-cylindrical cathode on its wall, a centrally disposed filament-like anode, and a cylindrical lens mounted on the wall opposite said cathode for focusing light passing through said apertures on to said cathode, said cells having a continuous unbroken element of a length sufficient to extend across the image frame, means for continuously moving said belt linearly at uniform speed in a direction transverse to that of said band so that said photo-electric cells as they pass the band move in a straight line, a source of current for said cells, means for connecting and disconnecting said source with each of said cells in turn as they pass into and out of, respectively, the scanning path of said band, an amplifier for amplifying the currents generated in said cells

and means for transmitting said amplified currents.

5. Television receiving apparatus including an endless belt bearing a plurality of tubular light-
5 sources, each of which comprises a single element tube of a length sufficient to extend across the image field, means for continuously moving said belt in a straight line at uniform speed in a direction perpendicular to the axes of said light-
10 sources, an endless metal band formed with a plurality of scanning apertures arranged in staggered formation, means for continuously moving said band linearly in a direction transverse to that of said belt and so that at any given time
15 that portion of the band affected by said light sources defines a straight line, and an optical system for focusing the light passing through said apertures.

6. Television receiving apparatus including an
20 endless belt bearing a plurality of tubular light sources each of which comprises a single element

tube of a length sufficient to extend across the image field and is provided with a cylindrical lens for focusing the emitted light into a narrow beam, means for continuously moving said belt in a straight line at uniform speed in a direction 5 perpendicular to the axes of said tubular light sources, an endless metal band the center portion of which is thinner than the edges and is formed with a plurality of square scanning apertures arranged in staggered formation and of 10 diameter not less than the thickness of said band, means for continuously moving said band linearly substantially in the plane in which said narrow beams are focused and in a direction transverse to that of said belt and so that at any 15 given time that portion of the band affected by the narrow beams defines a straight line, and an optical system for focusing the light passing through said apertures.

HANS KNUDSEN. 20
